(57) **CLAIM**

The ornamental design for a car latch pedal as shown and described.

DESCRIPTION

FIG. 1 is a top perspective view of a car latch pedal showing the new design;

FIG. 2 is a bottom perspective view thereof;

FIG. 3 is a left view thereof;

FIG. 4 is a right view thereof;

FIG. 5 is a rear view thereof;

FIG. 6 is a front view thereof;

FIG. 7 is a top view thereof;

FIG. 8 is a bottom view thereof;

FIG. 9 is an enlarged detail view showing area 9 in FIG. 1; and,

FIG. 10 is a top perspective view thereof, shown in a folded state.

The dashed broken lines illustrate portions of the car latch pedal which form no part of the claimed design. The dash-dot broken lines showing the boundaries and lead lines for the enlarged detail view forms no part of the claimed design.
